UNITED STATES PATENT OFFICE

2,088,437

GAS LIQUEFYING APPARATUS

Chester W. Rice, Schenectady, N. Y., assignor to
 General Electric Company, a corporation of
 New York

Application December 5, 1936, Serial No. 114,411

14 Claims. (Cl. 62—122)

My invention relates to gas liquefying apparatus and particularly to such apparatus of the regenerative type.

In gas liquefying apparatus of the regenerative type the gas is first compressed to a high pressure and is cooled by water or ice and is also dried and purified to remove moisture and other foreign matter. The compressed gas is then passed through an extended coil of tubing arranged within a thermally insulated casing and is discharged through a throttle valve into a liquefying chamber within the casing. The gas discharged through the throttle valve is slightly cooled by the Joule-Thomson effect and the cooled gas is removed from the liquefying chamber through a tube arranged in heat exchange relation with the coiled high pressure inlet conduit, or it is circulated over the turns of the inlet conduit and is returned to the compressor. The cooled gas removed from the liquefying chamber reduces the temperature of the high pressure gas entering the chamber. A regenerative effect is thereby obtained, and after the apparatus has been in operation a sufficient length of time the high pressure gas is cooled down so that a portion of it is liquefied on being discharged into the liquefying chamber, the liquefied gas being collected at the bottom of the chamber. Additional gas to make up for the liquefied gas enters the apparatus on the intake side of the compressor, a make-up compressor being provided in some cases to pump in the additional gas when required.

The rate of liquefaction of gas in regenerative liquefying apparatus depends upon the rate at which the heat energy may be removed from the gas passing into the liquefying chamber. It is, therefore, desirable to remove as much energy as possible from the gas as it enters the chamber. Accordingly, it is an object of my invention to provide an improved apparatus for liquefying gases having an arrangement for increasing the rate of liquefaction of gas.

Another object of my invention is to provide a gas liquefying apparatus having an arrangement for removing energy from the gas by utilizing the transformation of a portion of the energy of the gas into sound energy.

A further object of my invention is to provide a gas liquefying apparatus of the regenerative type having an auxiliary arrangement utilizing the formation and absorption of sound energy to increase the rate of liquefaction of gas in the apparatus.

55 Further objects and advantages of my inven-

tion will become apparent as the following description proceeds, and the features of novelty which characterize my invention will be pointed out with particularity in the claims annexed to and forming a part of this specification. 5

For a better understanding of my invention reference may be had to the accompanying drawing in which Fig. 1 is a sectional view of a gas liquefying apparatus embodying my invention, the compressor, purifier and pre-coolers 10 being shown diagrammatically; Fig. 2 is a detail sectional view of the throttle valve and sound producing device of Fig. 1, showing the adjusting or control mechanism; and Fig. 3 is an enlarged sectional view of the throttle valve and 15 sound producing device.

Referring now to the drawing in Fig. 1, I have shown a gas liquefying apparatus of the regenerative type including a thermally insulated casing 10 containing a gas liquefying chamber 11 formed with metal walls 11a, regenerative heat exchange conduits 12 and a throttle valve arranged in a heavy metal block 13, a compressor 14, compressed gas coolers 15 and 16 and a purifier 17. During the operation of the 25 apparatus gas is compressed by the compressor 14 to a high pressure, say 3,000 pounds per square inch, and is discharged through the conduit 18. The compressed gas is initially cooled in the cooler 15, provided with a conduit 19 for 30 circulating cooling water or other fluid therethrough. Moisture and other impurities in the gas are then removed by the purifier 17. The dehydration and purification of the gas is accompanied by a rise in temperature and the second 35 cooler 16 is provided to reduce the temperature of the purified gas. The cooler 16 utilizes ice or some other low temperature cooling substance. The cooled high pressure gas then enters the casing 10 through a connection 20 and a conduit 21. The 40 conduit 21 is connected through a fitting 22 with the coiled conduits 12, comprising three tubes secured together and arranged in a passage 24 within the casing 10. The conduits 12 comprise a large number of turns arranged closely together 45 within the passage 24. For purposes of illustration a few turns only have been indicated. The gas then passes from the conduits 12 into the block 13 through a fitting 26. Within the block 13 is a throttle valve 27 shown in Fig. 2. 50 The compressed gas passes through the valve 27 and into an opening 28 in the block 13 and thence into the chamber 11. On passing through the valve 27 the pressure of the gas is reduced substantially to atmospheric pressure and the 55

gas is cooled slightly due to the Joule-Thomson effect. This slightly cooled gas is discharged from the chamber 11 through a perforated plate 29 at the bottom of the passage 24 and passes through the passage 24 in heat exchange relation with the conduits 12 and upwardly through a perforated plate 30 and a body of sound absorbing material 31 arranged in the upper portion of the passage. The purpose of this sound absorbing material will be explained later. Since the gas has been slightly cooled by passage through the valve 27 this cooling effect is available for lowering the temperature of the high pressure gas within the conduits 12. The high pressure gas, therefore, is lowered in temperature and on passing through the throttle valve 27 is lowered still more. There is, therefore, a continual decrease in the temperature of the high pressure gas which provides the regenerative effect utilized for liquefying the gas. The low pressure gas is removed from the passage 24 through a connection 32 and flows through a conduit 33 to an intake chamber 34 and thence returns to the compressor through an intake connection 35. Additional gas may be drawn into the apparatus through an inlet 36 communicating with the inlet chamber 34. As the apparatus continues to operate the temperature of the gas discharged into the chamber 11 will 30 continue to be lowered until it is sufficiently low that a portion of the discharged gas is liquefied; the liquid collecting at the bottom of the chamber 11 and being withdrawn through a tube 37 provided with a valve 38.

35 The rate at which the gas passes through the valve 27 may be controlled by an adjusting knob 39 connected to the valve through a rod 40. The rod 40 extends upwardly from the valve 27 to the outside of the casing 10 through a tube 41 and is provided with threads 42 whereby the 40 position of the valve 27 with respect to its seat, indicated at 43, may be adjusted.

In order to increase the rate at which the temperature of the gas is reduced and, therefore, the rate at which the gas is liquefied by the apparatus, I provide an auxiliary arrangement for converting a portion of the energy of the gas into sound energy within the liquefying chamber 11 and for transmitting or conducting the sound energy to a point remote from the chamber 11 and there dissipating the energy by converting it into heat. The removal of a portion of the energy of the gas in the chamber 11 by conversion into sound energy reduces the temperature of the gas discharged into the chamber. The reduced temperature is maintained by removing the sound energy and dissipating it at a point remote from the cold chamber so that the reconversion of the sound energy into heat occurs in a place where the heat is not available to reheat the gas in the chamber. It is readily apparent that this process increases the rate of cooling of the gas. In order to accomplish the foregoing I provide a whistle comprising a bell 44 arranged in the jet of gas flowing from the throttle valve 27 through a whistle throat 43a directly below the valve seat 43, and I provide a sound transmitting or conducting passage comprising a plurality of concentric ducts 45 extending upwardly from the chamber 11 and surrounding the passage 24. In the upper portion of the casing 10 and in communication with the upper ends of the ducts 45, I provide a body of sound absorbing material 46. The sound produced by the whistle 44 is conducted upwardly through the ducts 45

to the sound absorbing material 46 where it is converted into heat energy. The metal walls 11a of the chamber 11 reflect the sound waves and very little of the energy is absorbed by the walls and reconverted into heat within the chamber. Any of the sound which may pass upwardly through the spaces between the turns of the conduit 12 will be dissipated in the sound absorbing material 31 previously referred to. The spaces in the passage 24 between the turns of the conduit 12 are small and provide an irregular path for sound; very little of the sound energy will, therefore, leave the chamber 11 through the passage 24.

The whistle bell 44 comprises a cup formed by a tube 47 threaded in the block 13 and having a rod 48 slidably mounted therein. The pitch of the sound produced by the whistle may be varied by adjusting the position of the rod 48 within the tube 47. The upper end of the tube 47 is beveled, as indicated at 49, to provide a sharp edge for the whistle. The efficiency of the whistle in converting into sound energy the energy of the gas issuing through the throat varies with the change in the length of the bell opening or distance between the whistle bell and the throat. In the drawing the bell opening is indicated at 25. Since the operating conditions of the apparatus may vary it is desirable to provide an arrangement for changing or adjusting the bell opening. Accordingly, I have provided a knob 50 secured to the lower end of the rod 47 outside of the casing 10; the adjustment being effected by turning the knob 50. In order to adjust the pitch of the whistle 35 I have provided a knob 51 secured to the lower end of the rod 48 and mounted in a threaded sleeve 52 formed on the knob 50. By turning the knob 50 the relative positions of the rod 48 and the tube 47 are varied. Normally the pitch of the whistle need be adjusted only during the assembly of the apparatus. The whistle should be adjusted with respect to the sound absorbing characteristic of the walls of the chamber 11, it being desirable that the pitch 45 of the sound be such that there is little absorption of the sound energy by the walls of the chamber 11 and, therefore, little reconversion of the energy into heat within the cold chamber. The whistle adjusting assembly is mounted in a tube 53 secured to the bottom portion 54 of the wall 11a in a bushing 55. In order to remove the heat produced by the absorption of the sound energy by the sound absorbing material 46 I provide a cooling coil 56 arranged within the sound absorbing material 46, so that water or other cooling fluid may be utilized to cool the sound absorbing material.

During the operation of the gas liquefying apparatus described above air or other gas is admitted to the compressor from the inlet chamber 34. The air is then compressed by the compressor 14 and passes through the cooler 15, the purifier 17 and the cooler 16. The cooled high pressure gas then flows into the liquefying casing 10 through connection 20 and passes through the turns of the coiled conduits 12 to the throttle valve 27. The air passing through the valve 27 is cooled by the Joule-Thomson effect and also by the conversion of a portion of the energy of the gas into sound energy at the whistle bell 44. The cooled gas then passes out of the chamber 11 through the passage 24 where it serves to lower the temperature of the high pressure gas in the coiled conduits 12 and is thereafter returned to the compressor through 75

- connection 32 and conduit 33. The sound produced by the whistle 44 is conducted through concentric ducts 45 to the sound absorbing material 46 where it is converted into heat energy.
- 5 The heat is removed from the sound absorbing material by cooling water flowing through the coil 56. As the cycle of operation continues the high pressure air flowing through the conduits 12 reaches a lower and lower temperature until the temperature is sufficiently low that a portion of the gas is liquefied on passing into the chamber 11. The liquid refrigerant collects in the bottom of the chamber 11 and may be withdrawn therefrom through the tube 31. Additional air is admitted to the chamber 34 through inlet connection 36 to make up for the air which is liquefied. The apparatus may, therefore, be operated to provide a continuous supply of liquid air.
- 20 It will be apparent from the foregoing that I have provided an arrangement for increasing the capacity of gas liquefying apparatus of the regenerative type. The additional parts required to provide the increased capacity are of simple and rugged construction, and include no moving parts subject to wear.

While I have shown and described my invention in connection with a gas liquefying apparatus of a specific type it will be understood that 30 it is applicable to other types of apparatus. I do not desire my invention to be limited to the specific construction shown and described and I intend in the appended claims to cover all modifications thereof which do not depart from 35 the spirit and scope of my invention.

What I claim is new and desire to secure by Letters Patent of the United States is:

1. A gas liquefying apparatus including a high pressure gas conduit, a gas liquefying chamber having thermally insulated walls, means for discharging into said chamber gas from said conduit, means for converting into sound energy a portion of the energy of said gas discharged into said chamber to reduce the temperature of said gas, means for discharging gas from said chamber, means for conducting away from said chamber sound energy produced therein to reduce the total energy of said gas within said chamber, and means remote from said chamber for dissipating said sound energy.

2. A gas liquefying apparatus of the regenerative type including a gas compressor and a high pressure gas conduit, means for discharging compressed gas from said compressor into said conduit, a gas liquefying chamber having thermally insulated walls, means including a throttle valve for discharging into said chamber gas from said conduit, means for converting into sound energy a portion of the energy of said gas discharged into said chamber to reduce the temperature of said gas, means for discharging gas from said chamber and for conveying said discharged gas from said chamber in heat exchange relation with said conduit to reduce the heat energy of the gas in said conduit, means for returning said discharged gas to said compressor, means for conducting away from said chamber sound energy produced therein to reduce the total energy of said gas within said chamber, and means remote from said chamber for dissipating said sound energy.

3. A gas liquefying apparatus including a thermally insulated casing having a gas liquefying chamber therein, means including an extended conduit for conveying high pressure gas to said

chamber, means for discharging into said chamber gas from said conduit, means for converting into sound energy a portion of the energy of said gas discharged into said chamber to reduce the temperature of said gas, means for discharging gas from said chamber, means for conducting away from said chamber sound energy produced therein to reduce the total energy of said gas within said chamber, and means remote from said chamber for dissipating said sound energy.

4. A gas liquefying apparatus including a thermally insulated casing having a gas liquefying chamber therein, means including an extended conduit for conveying high pressure gas to said chamber, means including a valve for discharging into said chamber gas from said conduit, means for converting into sound energy a portion of the energy of said gas discharged into said chamber to reduce the temperature of said gas, means for discharging gas from said chamber, means including a duct within said casing for conducting away from said chamber sound energy produced therein to reduce the total energy of said gas within said chamber, and means remote from said chamber for dissipating said sound energy.

5. A gas liquefying apparatus including a thermally insulated casing having a gas liquefying chamber arranged therein, means including a conduit having a plurality of coils arranged within said casing for conveying high pressure gas to said chamber, means including a throttle valve for discharging to said chamber gas from said conduit, means for converting into sound energy a portion of the energy of said gas discharged into said chamber to reduce the temperature of said gas, means for discharging gas from said chamber and for conveying said discharged gas through said casing in heat exchange relation with said conduit, means arranged within said casing and surrounding said coils for conducting away from said chamber sound energy produced therein to reduce the total energy of said gas within said chamber, and means remote from said chamber for dissipating said sound energy.

6. A gas liquefying apparatus including a thermally insulated casing having a gas liquefying chamber therein, means including an extended conduit for conveying high pressure gas to said chamber, means including a valve for discharging into said chamber gas from said conduit, means including a whistle for converting into sound energy a portion of the energy of said gas discharged into said chamber to reduce the temperature of said gas, means for discharging gas from said chamber, means for conducting away from said chamber sound energy produced therein to reduce the total energy of said gas within said chamber, and means remote from said chamber for dissipating said sound energy.

7. A gas liquefying apparatus including a thermally insulated casing having a gas liquefying chamber therein, means including an extended conduit for conveying high pressure gas to said chamber, means including a valve for discharging into said chamber gas from said conduit, means including a whistle for converting into sound energy a portion of the energy of said gas discharged into said chamber to reduce the temperature of said gas, means including a metal block for supporting said valve and said whistle within said chamber, said block having an open-

ing in the center thereof for the discharge of gas from said valve into said chamber, means for discharging gas from said chamber, means for conducting away from said chamber sound energy produced therein to reduce the total energy of said gas within said chamber, and means remote from said chamber for dissipating said sound energy.

8. A gas liquefying apparatus including a thermally insulated casing having a gas liquefying chamber therein, means including an extended conduit for conveying high pressure gas to said chamber, means including a valve for discharging into said chamber gas from said conduit, means including a whistle for converting into sound energy a portion of the energy of said gas discharged into said chamber to reduce the temperature of said gas, means for adjusting the bell opening of said whistle to vary the efficiency of said whistle, means for discharging gas from said chamber, means for conducting away from said chamber sound energy produced therein to reduce the total energy of said gas within said chamber, and means remote from said chamber for dissipating said sound energy.

9. A gas liquefying apparatus including a thermally insulated casing having a gas liquefying chamber therein, means including an extended conduit for conveying high pressure gas to said chamber, means including a valve for discharging into said chamber gas from said conduit, means including a whistle for converting into sound energy a portion of the energy of said gas discharged into said chamber to reduce the temperature of said gas, means for adjusting the bell opening of said whistle to vary the efficiency of said whistle, means for varying the pitch of the sound produced by said whistle, means for discharging gas from said chamber, means for conducting away from said chamber sound energy produced therein to reduce the total energy of said gas within said chamber, and means remote from said chamber for dissipating said sound energy.

45 10. A gas liquefying apparatus including a thermally insulated casing having a gas liquefying chamber therein, means including an extended conduit for conveying high pressure gas to said chamber, means including a valve for discharging into said chamber gas from said conduit, means including a whistle for converting into sound energy a portion of the energy of said gas discharged into said chamber to reduce the temperature of said gas, means for discharging gas from said chamber, means including a duct within said casing for conducting away from said chamber sound energy produced therein to reduce the total energy of said gas within said chamber, and means including a body of sound absorbing material arranged within said casing remote from said chamber for dissipating said sound energy.

11. A gas liquefying apparatus including a thermally insulated casing having a gas liquefying chamber arranged therein, means including a conduit having a plurality of coils arranged within said casing for conveying high pressure gas to said chamber, means including a throttle valve for discharging into said chamber gas from said conduit, means including a whistle for converting into sound energy a portion of the energy of said gas discharged into said chamber to re-

duce the temperature of said gas, means extending through said casing for adjusting the bell opening of said whistle to vary the efficiency of said whistle, means for discharging gas from said chamber and for conveying said discharged gas through said casing in heat exchange relation with said conduit, means arranged within said casing and surrounding said coils for conducting away from said chamber sound energy produced therein to reduce the total energy of said gas within said chamber, and means remote from said chamber for dissipating said sound energy.

12. A gas liquefying apparatus including a thermally insulated casing having a gas liquefying chamber therein, means including an extended conduit for conveying high pressure gas to said chamber, means including a valve for discharging into said chamber gas from said conduit, means for converting into sound energy a portion of the energy of said gas discharged into said chamber to reduce the temperature of said gas, means for discharging gas from said chamber, means including a duct within said casing for conducting away from said chamber sound energy produced therein to reduce the total energy of said gas within said chamber, means including a body of sound absorbing material arranged within said casing remote from said chamber for dissipating said sound energy, and means for cooling said sound absorbing material to remove the heat produced by the dissipation of said sound energy.

13. A gas liquefying apparatus of the regenerative type including a gas compressor and a high pressure gas conduit, means for discharging compressed gas from said compressor into said conduit, a gas liquefying chamber having thermally insulated walls, means including a throttle valve for discharging into said chamber gas from said conduit, means including a whistle for converting into sound energy a portion of the energy of said gas discharged into said chamber to reduce the temperature of said gas, means extending through said casing for adjusting the bell opening of said whistle to vary the efficiency of said whistle, means for discharging gas from said chamber and for conveying said discharged gas from said chamber in heat exchange relation with said conduit to reduce the heat energy of the gas in said conduit, means for returning said discharged gas to said compressor, means for conducting away from said chamber sound energy produced therein to reduce the total energy of said gas within said chamber, and means remote from said chamber for dissipating said sound energy.

14. In a gas liquefying apparatus of the regenerative type, an insulating casing having a gas liquefying chamber therein, means for supplying compressed gas to said apparatus, means for discharging said compressed gas into said chamber and utilizing the Joule-Thomson effect for cooling said gas, auxiliary means for supplementing said last-mentioned means to further cool the gas discharged into said chamber, said auxiliary means comprising means for converting a portion of the energy of said compressed gas into sound energy to lower the temperature of said gas, and means for dissipating said sound energy at a place remote from said gas liquefying chamber.

CHESTER W. RICE.
